(57) **CLAIM**

The ornamental design for an adapter for power tools as shown and described.

DESCRIPTION

FIG. 1 is a perspective view of an adapter for power tools showing my new design in accordance with a first embodiment;

FIG. 2 is a front elevation view thereof, to which the rear elevation view is identical;

FIG. 3 is a left side elevation view thereof, to which the right side elevation view is identical;

FIG. 4 is a top plan view thereof;

FIG. 5 is a bottom plan view thereof;

FIG. 6 is a perspective view of an adapter for power tools showing my new design in accordance with a second embodiment;

FIG. 7 is a front elevation view thereof, to which the rear elevation view is identical;

FIG. 8 is a left side elevation view thereof, to which the right side elevation view is identical;

FIG. 9 is a top plan view thereof; and,

FIG. 10 is a bottom plan view thereof.

In Embodiment 2, represented by FIGS. 6-10, the shank of the adapter for power tools is shown with a break in its length. The appearance of any portion of the adapter for power tools between and within the broken lines forms no part of the claimed design.
